[57] **CLAIM**

The ornamental design for a golf club holder, as shown and described.

DESCRIPTION

FIG. 1 is a top plan view of a golf club holder showing my new design;

FIG. 2 is a bottom plan view thereof;

FIG. 3 is a front elevation view thereof, rotated 90° from FIG. 1;

FIG. 4 is a right side elevation view thereof, rotated 90° from FIG. 1, the opposite side being a mirror image; and,

FIG. 5 is a rear elevation view thereof, rotated 90° from FIG. 1.
